UNITED STATES PATENT OFFICE.

MAX HERMSDORF, OF ESSEN-ON-THE-RUHR, GERMANY, ASSIGNOR TO FRIED. KRUPP AKTIENGESELLSCHAFT, OF ESSEN-ON-THE-RUHR, GERMANY.

BREECH-CLOSURE.

1,098,261.

Specification of Letters Patent.

Patented May 26, 1914.

Application filed September 12, 1910. Serial No. 581,620.

To all whom it may concern:

Be it known that I, MAX HERMSDORF, a subject of the Emperor of Germany, and a resident of Essen-on-the-Ruhr, Germany, have invented certain new and useful Improvements in Breech-Closures, of which the following is a specification.

The object of this invention is to make a breech closure with a catch that prevents the ammunition from sliding back or falling out of the gun chamber when the gun is elevated. Known devices of this kind are arranged so that they, at the insertion of the ammunition (in loading) in the gun chamber, are transferred by the ammunition nearly in the thrown out position and then by a spring are brought into their holding or catching position. Such an arrangement of the device requires that it must be thrown out by the extractor or any other part of the breech mechanism, before the extraction of cartridge-case takes place, so that it does not check the extraction of the cartridge-case. This invention aims at arranging catches of this kind, so that they may function independent of other parts of the breech mechanism.

In the accompanying drawing, the invention is shown for use in connection with a wedge breech-closure.

Figure 1 is a vertical, longitudinal section through the breech of the gun, with the wedge removed. Fig. 2 is a top plan view of the catch and a part of the gun breech. Fig. 3 is a rear view of Fig. 1 partly in section at 3—3 of Fig. 1. Fig. 4 is a part of the representation in Fig. 1 with the catch in a different position, and Fig. 5 a rear view of Fig. 4 partly in section 5—5 of Fig. 4.

Referring to the structure in detail A is the breech of the gun and the breech-opening is indicated by A'. Near the front-face of the breech in the trough-shaped wall a² of the breech-opening A' is a recess a³. The wall a² terminates with a cylindrical face, the diameter of which is nearly the same as the flange of the cartridge-case. In the recess a³ are two, double-armed levers or latches C, C' and D, D' carried on bolts c² and d² and adapted to rock but not to slide. The turning axes of these latches are parallel to the gun axis. The inner arms C' and D' of the latches engage with each other. Both arms of the latch D D' and the arm C of the latch

C C' have measured lengthwise in the gun 55 considerably less breadth than the space a³, while the latch arm C' measured similarly has the same breadth as the recess a³. This arm, which grips over the latch arm D' is intended to bring about the drawing in of 60 the latches. A spring E holds the latches in the downpressed position in the recess a³ as indicated in Figs. 1 to 3. The recess has such a shape, transversely to the gun-axis, that the cartridge case with its flange B 65 shown in dot and dash-line in Fig. 3 may slide along on the sides a⁴ of said recess and over the latch arms C C' and D D' without throwing in the latch. On the other hand it is possible for the projectile—the base of 70 which is indicated with dot-and-dash-lines in Figs. 4 and 5—to enter deep enough in the recess a³ that it presses down the latch-arm C' and thereby puts the latches in the stop or holding position.

Before the loading of the gun, the latches C C' and D D' take the position shown in Figs. 1 to 3. In inserting the projectile in the breech opening it slides along on the latches C C' and D D'. As soon as it has 80 reached the position indicated by dot-and dash-lines in Figs. 4 and 5, (i. e. as soon as the base of the projectile G has left the latch arms C, D and lies on the extension of the latch arm C' that is nearest the chamber) 85 then the latch arm C' will be pressed down by the weight of the projectile and as a consequence the latch arms C, D will be turned up behind the base of the projectile into the position shown in Figs. 4 and 5. The projectile is now prevented from sliding back 90 out of the breech opening. When the projectile is pushed fully home, and as soon as its base has left the latch-arm C', the latches will return to the position shown in Figs. 95 1 to 3, being acted upon by the spring E. The insertion of the cartridge in the chamber of the gun, will not influence the latches C C' and D D', as the base flange B of the cartridge case has a considerably larger 100 diameter than the base of the projectile and, consequently can slide along the trough shaped walls of the breech opening as well as on the edges a⁴ of the recess a³ without pressing down the latch-arm C'; and for 105 this reason the latches do not prevent the ejection of the cartridge case. By placing the catch near the face of the breech the

loading of the gun is facilitated, as the projectile does not need to be pushed far into the gun to get the catch into operation.

Without changing the substance of the invention, the spring E which holds the latch in the pressed down position, might be left out, as the weight of the latches C C' and D D' is so divided in relation to their turning axis that the latches from the working 10 of the weight will return into their retracted position.

What is claimed is:—

1. The combination with a gun barrel having a breech closure opening, of a means 15 for preventing the sliding back of the projectile comprising a latch mounted in the wall of the breech, means adapted to hold said latch out of the engaging position before and after the loading operation, and 20 means adapted to throw said latch into the engaging position by co-operation with the projectile to be inserted.

2. The combination with a gun barrel having a breech closure opening, of a means 25 for preventing the sliding back of the projectile comprising a latch arranged in the wall of the breech and adapted to be out of the engaging position before and after the loading operation, and an inwardly extend- 30 ed part on the latch adapted to be depressed by the pressure of the projectile resting thereagainst and adapted to throw thereby said latch into the engaging position.

3. The combination with a gun barrel 35 having a breech closure opening, of a means for preventing the sliding back of the projectile, comprising a latch pivotally mounted in the wall of the breech and adapted to be out of the engaging position before and after 40 the loading operation, and an inwardly extended part on the latch adapted to be depressed by the weight of the projectile resting thereagainst and adapted to throw thereby said latch into the engaging position, said

latch and inwardly extended part being 45 mounted within a recess of the breech, the operating point of said inwardly extended part being normally retired below the profile of a cylindrical surface of the wall of the breech, the diameter of which is ap- 50 proximately the same as that of the cartridge but larger than that of the projectile, so as to permit the latch to be thrown into the engaging position by the weight of the projectile during the loading operation, but 55 permitting of the insertion of the cartridge without effecting the actuation of the latch.

4. The combination with a gun barrel having a breech closure opening, of a means located in a recess in close proximity to the 60 rear face of the breech of the gun barrel for preventing the sliding back of the projectile; said means comprising a pair of trans- 65 versely disposed two-armed levers pivotally mounted within said recess, an inner arm of one of the levers overlying the inner arm of the other lever and formed with an inwardly disposed member, said levers constructed to support the projectile during a part of the loading operation, and said in- 70wardly disposed member adapted to be engaged by the projectile on the further loading operation and effect to throw into en- gaging position the outer arms of the levers through the medium of the engaged inner 75 arms thereof; said inwardly disposed member adapted to be released and the levers returned to the inoperative position on the completion of the loading of the projectile, and the wall adjacent the recess permitting 80 of the loading of the cartridge out of contact with the levers.

The foregoing specification signed at Germany, this 24th day of August, 1910.

MAX HERMSDORF.
